UNITED STATES PATENT OFFICE

2,640,257

CAN OPENER

Herbert A. Berkman, Chicago, Ill., assignor to
Zim Manufacturing Company, a corporation of
Illinois

Application August 14, 1952, Serial No. 304,369

4 Claims. (Cl. 30—9)

1

The present invention relates to can opening tools of the type disclosed in Patent 2,423,221, granted July 1, 1947, and it has for its object to improve the construction and operation of the same.

In the aforesaid can opener the bead around the top of a can is caused to rest on a feed wheel the periphery of which is serrated, while the can top is engaged by a rotary slitting cutter. In the device of the patent the cutter is solidly mounted for rotation about a fixed axis; whereas the feed wheel is mounted on a swinging arm so that it may be swung away from the cutter to permit a can to be entered or removed, and to be moved toward the cutter to cause the latter to puncture the can close to the bead. Furthermore, there is on the body of the tool a short, horizontal flange or lip that contacts the side of a can remote from the top to hold the body of the can clear of the feed wheel.

There are two defects in this old type of tool. In the first place, with the feed wheel mounted on a swinging arm, not only is the cost of manufacture greater than is desirable, but it is difficult to achieve and maintain the proper relation between the cutter and the feed wheel. In the second place, the flange or lip that is intended to hold the body of the can away from the feed wheel actually drives the can against the trailing edge of the wheel, in many instances, so that cans are often badly scratched.

The first of these defects I overcome by mounting the feed wheel directly on the body portion of the tool, so that it rotates about a fixed axis, while the cutter is mounted in a manner to ensure the same solid support and yet permit bodily movements to open and close the tool. Specifically, I mount the cutter eccentrically on one end of a heavy spindle or trunnion and permit the latter to make a quarter turn for opening and closing the tool. The thrust of the can against the cutter, while the can top is being severed is resisted by a fixed stop, so that the conditions during this time are the same as though the cutter were mounted directly on the body of the tool and had no bodily movement.

The second defect is avoided through the provision, on the aforesaid lip or flange, of an off center projection, preferably a roller, that constitutes the point or area of contact with the can body.

The various features of novelty whereby the present invention is characterized will herein-after be pointed out with particularity in the claims; but, for a full understanding of the in-

2

vention and of its objects and advantages, reference may be had to the following detailed description taken in connection with the accompanying drawing, wherein:

Fig. 1 is a front view, a small portion being in section, of a can opener embodying the present invention in a preferred form, the device being shown open.

Fig. 2 is a top plan view of the new can opener.

Fig. 3 is a section along the planes of stepped line 3—3 of Fig. 1.

Fig. 4 is a front view of one end of the can opener, closed, with the rotary cutter omitted.

Figs. 5 and 6 are, respectively, a side view and an end view of the forward end of the supporting trunnion for the cutter.

Fig. 7 is a section on line 7—7 of Fig. 1.

Referring to the drawing, 1 is a conventional body member in the form of a long, narrow, flat plate arranged on edge. A conventional feed wheel 2 is fixed on the forward end of a shaft 3 that extends through a heavy block 4, preferably a die casting, secured to the rear side of the body member at the free end of the latter. On the rear end of the shaft is a conventional handle 5 for turning the same. Shaft 3 has a limited lengthwise movement, a spring 6 tending constantly to hold it in its forward position. In the exact structure illustrated, the spring is located in an annular space between the inner surface of bore 7 and a section 3a of reduced diameter of the shaft. The forward end of the spring abuts against the shoulder at the juncture of the two shaft sections. Feed wheel 2 has a hub 2a, larger in diameter than the shaft, movable into and out of engagement with block 4 through a hole 8 in the body member.

Block 4 has at the top, on the rear side, a sleeve-like hub 4a the bore in which extends through the block from rear to front. The axis of hub 4a is inclined downwardly and forwardly and also slightly in the direction of the free end of the body member. Fitting rotatably in this hub is a trunnion or short piece of heavy shaft 10 that protrudes from the rear end of the hub. The trunnion is provided with an actuating lever 11 in the form of a sturdy rod extending at one end through and being a driven fit in the rearwardly projecting part of the trunnion. Forming the extreme forward end of the trunnion is a cam block 12, a portion of which projects well beyond the cylindrical surface of the trunnion. The cam contains a screw-receiving hole 13, that parallels the axis of the trunnion but is eccentric with respect thereto. A conventional rotary

50 55 60 65 70 75 80 85 90 95

cutter 14, having on the rear side a hub 14^a, is secured to the trunnion by a screw 15 entered into hole 13; the screw forming a stub shaft on which the cutter is free to rotate.

On the front side of the body member is an arm, 16, in the form of a long, narrow, flat plate, pivotally connected to the body member, at a point inwardly and remote from the feed wheel and the cutter, by a rivet 17. This arm extends to the free end of the body member. A second rivet 18, extends through arm 16 and through a short slot 19 in the body member, to limit the swinging movements of the arm. Arm 16 has at its lower edge, at a slightly higher level than the top of the feed wheel, a forwardly facing flange 16^a. A doorway 20 is cut through this flange and up into the arm in the area of the forward end of trunnion 10 and the cutter. At the top of this doorway is a forwardly projecting flange or hood 16^b that overlies cam 12 on the trunnion. Arm 16 is normally held down, with rivet 18 at the lower end of slot 19 as in Fig. 4, by a strong coil spring 21. This spring is housed in an open-ended cylindrical shell 22 integral with the arm and closed at the lower end by the adjacent portion of flange 16^a. A tongue 23 is partially severed from that part of arm 16 that forms the shell; the tongue being bent back past the end and against the rear face of the body member 1 to hold the free end 30 of the arm against the body member. On the body member, at some distance above sleeve 22 when arm 16 is down, is a forwardly projecting lip 1^a. Fixed to this lip, and extending down into the sleeve, is a post 24 provided with a downward extension 24^a of reduced diameter. This extension reaches well down into the spring and centers the same.

As best shown in Figs. 1 and 4, there is on the forward side of block 4, beside trunnion 10, a lug 25. Cam 12, on the front end of the trunnion, has a tip or nose 12^a that strikes this lug when the combined screw and stub shaft 15 is closest to the feed wheel, as in Fig. 4. The cutter carried by stub shaft 15 is at this time in its lowermost position, namely that occupied after it has punctured the can top. Lever 11 at this time rises almost vertically from the body member 1. When this lever is swung through about a quarter turn in the counterclockwise direction viewed as in Fig. 4, nose 12^a recedes from stop lug 25 and a flat peripheral portion 12^b on element 12 engages the under side of hood 16^b, arresting the cutter in its raised, idle position, as in Fig. 1. Flattened portion 12^b is so placed that when lever 11 is swung up from its horizontal position, there is an upward push on flange 16^b, on arm 16, causing the arm to swing up a little. Then the arm is allowed to swing down again until the flattened edge portion 12^b contacts throughout its whole length with the under side of the hood. The tool is therefore yieldingly locked in its open state, with lever 11 down and out of the way.

During the cutting operation, the feed wheel turns in the counterclockwise direction, as viewed in Figs. 1 and 4, the thrust against the cutter being in the direction to press the cam block 12 against stop 25; and, therefore, no forces are acting in a manner to turn the trunnion back and lift the cutter out of the can. At the end of a cutting operation, the can is readily freed by swinging lever 11 from the upright to the horizontal position. While the cutting proceeds,

flange 16^a on arm 16 holds the can firmly against the feed wheel.

Along the lower edge of the body member is a horizontal flange or lip 1^b which, heretofore has been used to engage the side of the can and prevent it from swinging against the side of the feed wheel. However, there is some frictional resistance between such a flange and a can body to interfere with a free turning movement of the can when driven by the feed wheel. I have discovered that it is this friction that causes cans to be thrown back against the edge of the wheel, well below the bead, so as to be scarred and scratched by the wheel.

In accordance with the present invention I arrange a small projection at the long, free edge of lip or flange 1^b, at a point that is a little nearer the free end of the body member than is the lowermost point of the cutter when the latter is down. In the preferred embodiment, the projection is a roller or thick disc 26 which lies flat against the flange and projects slightly beyond the said edge of the flange. In the particular construction illustrated, the roller underlies the flange and is rotatably supported by a rivet 27. As best shown in Fig. 8, the rivet has an enlarged section 27^a adjacent to the roller engaging head 27^b. This permits the rivet to be fixed to the flange without binding the roller which, therefore, may turn freely. The axis of the rivet is displaced from a vertical plane containing the axis of the feed wheel shaft 3, toward the outer end of the body member, about one eighth of an inch. When a can is inserted in the tool, the can body engages the roller outwardly from said plane and, being held down by flange 16^a, the can remains upright with the point of contact between the roller and the can body trailing a point on the can that has already reached said plane, as the feed wheel turns the can during a cutting operation. Thus the roller not only reduces the friction tending to retard the desired turning of a can, but it also serves as a stop to prevent objectionable can movement tending to cause the can to be scratched and scarred.

While I have illustrated and described in detail only a single preferred embodiment of my invention, I do not desire to be limited to the exact details so illustrated and described; but intend covering all forms coming within the definitions constituting the appended claims.

I claim:

1. In a can opener having a body member, a feed wheel mounted on and toward the outer end of such member, a rotary cutter on said member 55 above the feed wheel and in cooperative relation thereto for cutting out the top of a vertically held can, and a horizontal forwardly projecting flange along the lower edge of the body member directly below the feed wheel; a small projection extending forwardly from the edge of the flange a little nearer said outer end of the body member than is a vertical plane containing the axis of the feed wheel, the projection being in position to engage the can body and compel it to turn freely during cutting operations, and a yieldable member in position to bear on the top of the can and hold the same in contact with the periphery of the feed wheel and against said projection.

2. A can opener as set forth in claim 1 wherein the projection is a roller the axis of which is spaced a substantial distance from the vertical plane containing the axis of the feed wheel.

3. A can opener as set forth in claim 1 wherein the projection is a roller the axis of which is par-

allel to and about an eighth inch away from the vertical plane containing the axis of the feed wheel.

4. A can opener comprising a body member, a feed wheel mounted on the front of the latter for rotation about a fixed axis, a sturdy journal extending through the body member above said wheel with its axis inclined downwardly from rear to front, a cutter mounted on the front end of the journal, eccentrically of the axis, for bodily movements from and toward the wheel as the journal is rocked, an arm mounted on the front of the body above the journal for limited swinging movements from and toward the latter, a spring acting on said arm and tending constantly to hold it in the position nearest the journal, a cam fixed to the front end of the journal behind the cutter, a lug on the body member beside the cam, said cam having a nose that engages said lug when the cutter is closest to said wheel, said cam also having a part to engage and cooperate with said arm yieldingly to lock the journal against movement in the direction to carry the

5

cutter toward said wheel when the cutter is farthest from the wheel, an operating lever fixed to the rear end of the journal, and means to rotate the feed wheel.

HERBERT A. BERKMAN.
